INVENTOR
Henry M. Fox
By W. W. Williamson Atty.

UNITED STATES PATENT OFFICE.

HENRY M. FOX, OF PHILADELPHIA, PENNSYLVANIA.

DRAWING INSTRUMENT.

Application filed April 14, 1923. Serial No. 632,035.

To all whom it may concern:

Be it known that I, HENRY M. FOX, a citizen of the United States, residing at Philadelphia, in the county of Philadelphia and

5 State of Pennsylvania, have invented new and useful Improvements in a Drawing Instrument, of which the following is a specification.

My invention relates to new and useful 10 improvements in a drawing instrument, and has for its object to provide an exceedingly simple and effective device of this character which may be made of such size as to be readily carried in the pocket of the user's 15 clothing and it may be used for producing straight lines, angular lines, circles of different sizes, drawing lines at right angles to another, measuring distances and measuring or laying out angles or degrees on a circle. 20 Another object of the invention is to form such a device from a sheet of suitable material thereby producing a body having two parallel straight edges, a straight edge at one end and at right angles to the parallel side 25 edges and an arcuate edge at the other end concentric with a hole in the body from which radiate lines to form a protractor.

A further object of the invention is to provide a plurality of holes adjacent the end 30 straight edge and equi-distant therefrom, said holes having a line bisecting them and parallel to the end straight edge to form a right angle with the parallel side edges whereby said holes and the line bisecting 35 them may be superimposed upon a delineated line for producing another line at right angles to said delineated line by the use of one of the side edges without the likelihood of the marking device slipping around a corner of the drawing instrument which would 40 form a deflecting mark.

A still further object of the invention is to provide a plurality of other holes adjacent one of the side edges and forming lines bisecting each one of said holes and one of the holes on the base line which is parallel to the end straight edge whereby different angles may be produced with respect to the base line.

50 With these ends in view, this invention

consists in the details of construction and combination of elements hereinafter set forth and then specifically designated by the claims.

In order that those skilled in the art to 55 which this invention appertains, may understand how to make and use the same, I will describe its construction in detail, referring by numerals to the accompanying drawing forming a part of this application, in 60 which:—

Fig. 1, is a face view of a drawing instrument embodying my invention.

Fig. 2, is a sectional edge view thereof.

In carrying out my invention as here embodied, 2 represents the body of the drawing instrument which may be formed from a sheet of suitable material such as, for instance, celluloid which is preferable because of its transparency. This body pref- 65 erably is relatively long and narrow so as to provide two parallel side straight edges 3 and 4, an end or base straight edge 5 at right angles to said side straight edges and an arcuate edge 6 at the end opposite the base 70 straight edge.

Associated with one of the side straight edges, as 3, is an English measure or rule 7 which is delineated upon one face of the body as by printing or slightly grooving the 80 body while associated with the other side straight edge 4 is a scale or metric measure 8 produced in the same manner as the measure or rule 7. In the body concentric with the arcuate edge 6 is a hole 9 from which 85 radiate lines 10 of different degrees and by placing the hole 9 over a point said lines may be used as a protractor for measuring angles and by rotating the instrument about the point with which the hole 9 coincides until 90 one of the lines 10 coincides with a delineated line on a surface marks may be produced around the arcuate edge 6 in alignment with any of the protractor lines 10 after which an angular line may be produced.

95 Adjacent the base or end straight edge are formed at least two holes 11 and 12 equi-distant from the base or end straight edge 5 and these holes are bisected by a base line 13 100

which will then be parallel to the base edge 5. A number of other holes 14, 15, 16, 17 and 18 are associated with the hole 12 and properly spaced therefrom, said holes representing degrees of a circle relative to the base line 13 which preferably are arranged equi-distant from the side straight edge 4. A number of lines 19, 20, 21, 22 and 23 each bisect one of the holes 14 to 18 inclusive and all of said lines bisect the other hole 11 on the base line so that with said base line the lines 19 to 23 inclusive form angles 15, 30, 45, 60 and 75 degrees respectively.

To produce any one of these angles the drawing instrument is laid upon a suitable surface by bisecting a suitable marking device, such as a pencil, through the holes 11 and 12 and in lines 14 to 18 inclusive lines of the desired angularity may be reproduced by afterwards joining the dots made by the marking device by the use of one of the straight edges of the drawing instrument when the latter is placed adjacent the dots thus giving the lines desired in the same manner as is generally accomplished by the use of a triangle. When it is desired to produce a line at right angles to a delineated line the holes 11 and 12 are caused to coincide with said delineated lines and then by using one of the side straight edges another line may be produced which may be caused to join the delineated line without the necessity of running the marking device to the end or corner of the drawing instrument so that a neat accurate line is produced without the likelihood of having a ragged or deflecting portion at the junction point with the said delineated line as often happens when the edge of an instrument is caused to coincide with the delineated line for the production of another as it often happens that the marking device will slip around the corner of the drawing instrument.

On the longitudinal center of the body 2 are formed a plurality of spaced holes 24 one of which may be used as a center for the insertion of an anchoring device, such as a pin, and the others then used for the insertion of a marking device and by moving said marking device the drawing instrument will cause said marking device to produce a circle or portion of a circle of the desired radius and for the centering hole I prefer to use that one of the series of holes 24 which is within the base line 13. All of the holes so far referred to are preferably of tapered formation as plainly shown in Fig. 2 in order that pointed devices, such as pencils, may readily fit therein. I have found that it is sometimes difficult to produce a circle with those lines which are closest to the centering hole and I have therefore provided the three apertures 25 of varying sizes by which circles may be produced equal to those that could be produced by

the use of three holes of the set 24 closest to a centering hole.

From the foregoing description it will be seen that this drawing instrument although relatively small and compact may be used for the production of many geometrical figures as well as for measuring distances and degrees. Such a device is particularly useful for a draftsman who is compelled to travel from place to place in making sketch drawings for the production of final drawings in the drafting room.

This instrument is also exceedingly useful to students in making reproductions of lesson drawings in a note book eliminating the necessity of carrying or using separate triangles, rules or scales, a protractor, compass and the like.

Of course I do not wish to be limited to the exact details of construction as herein shown as these may be varied within the limits of the appended claims without departing from the spirit of my invention.

Having thus fully described my invention, what I claim as new and useful is:—

1. A drawing instrument comprising a relatively long and narrow strip of sheet material having two parallel straight edges, a base edge at one end lying at right angles to the edges and an arcuate edge at the opposite end, said straight edges having scales associated therewith, said body having at least two holes formed therein adjacent the base edge equi-distant from said edge and bisected by a base line, said body further having a hole therein homocentric with the arcuate edge and bisected by lines radiating therefrom to the said arcuate edge.

2. A drawing instrument comprising a relatively long and narrow strip of sheet material having two parallel straight edges, a base edge at one end lying at right angles to the edges and an arcuate edge at the opposite end, said straight edges having scales associated therewith, said body having at least two holes formed therein adjacent the base edge and bisected by a base line, said body also having holes formed therein in spaced relation to one of the holes bisected by the base line with a line bisecting each of said last named holes and the other hole which is bisected by the base line, said body further having a hole formed therein homocentric to the arcuate edge with radiating lines bisecting said hole and running to the arcuate edge.

3. A drawing instrument comprising a relatively long and narrow strip of sheet material having two parallel straight edges, a base edge at one end lying at right angles to the edges and an arcuate edge at the opposite end, said straight edges having scales associated therewith, said body having at least two holes formed therein adjacent the

base equi-distant from said edge and bisected by a base line, said body also having holes formed therein in spaced relation to one of the holes bisected by the base line with a line bisecting each of said last named holes and the other hole which is bisected at the base line, said body further having a hole formed therein homocentric to the arcu-

ate edge with radiating lines bisecting said hole and running to the arcuate edge, said body also having a series of spaced holes formed in the longitudinal center and another set of three holes of varying sizes. 10

In testimony whereof, I have hereunto affixed my signature.

HENRY M. FOX.
